United States Patent Office

Des. 220,988
Patented June 22, 1971

220,988

JEWELRY BOX

Jacqueline Rosenbluth, 302 E. 18th St.,
New York, N.Y. 10003

Filed Dec. 23, 1969, Ser. No. 20,611

Term of patent 14 years

Int. Cl. D3—02

U.S. Cl. D87—1

FIG. 1.

FIG. 2.

FIG. 3.

FIG. 4.

FIG. 5.

FIG. 7

FIG. 1 is a top plan view of a jewelry box showing my new design.

FIG. 2 shows one side as seen in direction of arrow 2 in FIG. 1.

FIG. 3 shows one side as seen in direction of arrow 3 in FIG. 1.

FIG. 4 shows one side as seen in direction of arrow 4 in FIG. 1.

FIG. 5 shows one side as seen in direction of arrow 5 in FIG. 1.

FIG. 6 is a perspective view of the jewelry box as seen in direction of arrow 6 in FIG. 1.

FIG. 7 is a perspective view thereof as seen in direction of arrow 7 in FIG. 1, showing two drawers in partially open position.

I claim:

The ornamental design for a jewelry box, as shown and described.
